UNITED STATES PATENT OFFICE

103,601

DESIGN FOR A COPY HOLDER

Arthur L. Slee, San Francisco, Calif.

Application January 22, 1937, Serial No. 67,245

Term of patent 14 years

To all whom it may concern:

Be it known that I, Arthur L. Slee, a citizen of the United States, residing in the city and county of San Francisco, and State of California, have invented a new, original, and ornamental Design for Copy Holders, of which the following is a specification, reference being had to the accompanying drawings, forming part thereof.

Fig. 1 is a perspective view,
Fig. 2 is a side elevation, and
Fig. 3 is a front elevation of a copy holder, showing my new design.

I claim:
The ornamental design for a copy holder, as shown.

ARTHUR L. SLEE.
